[57] CLAIM

The ornamental design for transfer tape holder, as shown and described.

DESCRIPTION

FIG. 1 is a top plan view of a transfer tape holder showing our new design;

FIG. 2 is a left side elevational view;

FIG. 3 is a front elevational view;

FIG. 4 is a right side elevational view;

FIG. 5 is a bottom plan view;

FIG. 6 is a rear elevational view;

FIG. 7 is a perspective view;

FIG. 8 is a top plan view of the cap, with the transfer tape holder removed for convenience of illustration;

FIG. 9 is a front elevational view of FIG. 8;

FIG. 10 is a right side elevational view of FIG. 8;

FIG. 11 is a top plan view of the transfer tape holder, with the cap removed for convenience of illustration;

FIG. 12 is a left side elevational view of FIG. 11;

FIG. 13 is a front elevational view of FIG. 11;

FIG. 14 is a bottom plan view of FIG. 11; and,

FIG. 15 is a rear elevational view of FIG. 11.
